(57) **CLAIM**

The ornamental design for a saw handle, as shown and described.

DESCRIPTION

FIG. 1 is a view in perspective of a saw handle.
FIG. 2 is a front view of the saw handle of FIG. 1.
FIG. 3 is a top plan view of the saw handle of FIG. 1.
FIG. 4 is a bottom view of the saw handle of FIG. 1.
FIG. 5 is a left end view of the saw handle of FIG. 1; and,
FIG. 6 is a right end view of the saw handle of FIG. 1.
The broken line portions of the disclosure are for illustrative purposes only and form no part of the claimed design.
